UNITED STATES PATENT OFFICE.

JACOB E. COLEMAN, OF CLARKSBURG, WEST VIRGINIA.

GAS-BURNER.

1,281,138.

Specification of Letters Patent.

Patented Oct. 8, 1918.

Application filed January 31, 1918. Serial No. 214,571.

To all whom it may concern:

Be it known that I, JACOB E. COLEMAN, a citizen of the United States, residing at Clarksburg, in the county of Harrison and 5 State of West Virginia, have invented certain new and useful Improvements in Gas-Burners, of which the following is a specification.

My invention consists in an improvement 10 in gas burners, particularly adapted to the combustion of fuel gas, and has for its object to provide a burner of simple and cheap construction adapted to provide for complete, accurate and economical mixture with air 15 and effective combustion of the fuel gas. It also has in view to deliver mixed gas and air to the combustion chamber of a furnace in a manner best adapted to effect complete combustion and utilization of fuel for quick 20 generation of heat.

The invention comprises a mixing chamber composed of a gas and air receiving head, a delivery conduit, and a terminal flare plate, constructed and adapted to operate in 25 the manner more particularly hereinafter described.

In the drawings:

Figure 1 is a central vertical sectional view of a boiler setting provided with my 30 improved burner;

Fig. 2 is an enlarged view of the burner in elevation, detached;

Fig. 3 is a plan view of the burner;

Fig. 4 is a longitudinal vertical section on 35 the line IV—IV of Fig. 3;

Fig. 5 is a cross sectional view on the line V—V of Fig. 2; and

Fig. 6 is a cross sectional view on the line VI—VI of Fig. 2.

Referring to the drawings, the burner as 40 a whole, which is shown in operative position within the furnace of a boiler setting of any usual or preferred construction, comprises a head 2 and a gas mixing conduit 3, or pipe, provided at its inner terminal end with the flare plate 4.

The head 2, which may be conveniently made in the form of a casting, is provided at its front end with a threaded opening 5 into which is introduced a gas supply pipe 6 with, if desired, a reducing bushing 7. An inner gas pipe 8 extends from such bushing connection inwardly through the open interior 9 of the head 2 and therebeyond, terminating within the conduit 3 at a suitable

distance to effect suction of the atmospheric air in the manner of an injector.

An advantage in using a bushing connection is that various sized pipes may be used for the gas supply, depending on the 60 volume, pressure, etc., also the size of the boiler, so that the size of the pipe can be changed as desired.

One or both sides of the head 2 extends laterally by air inlet portions 10, each of 65 which is provided with an air regulating or closing plate or damper 11 adjustably secured to the end of the hollow air inlet portion 10 by an adjustable securing thumb screw 12. By means of such mounting, the 70 damper plate 11 at either side may be fixedly located at any desired position, either entirely open, or partly open, or entirely closed, whereby to regulate the amount of incoming air, or to entirely shut off the air supply. 75 The outer face of the air inlet extension 10, and the inner face of the damper plate 11 are preferably faced or finished, to provide for accurate fitting and avoidance of leakage.

A particular advantage of the air control 80 dampers, as thus arranged, is that they may be individually set at one side or the other with respect to the air inlet opening to admit the proper proportion of air, having regard to the pressure and amount of the gas 85 supply. A further particular advantage is that the mixing head, being usually located in an outside or exposed position, and subject to air drafts or wind pressure, the dampers may be set with respect thereto so 90 as to very accurately control the amount of incoming air.

Thus should currents of air be blowing against one side only of the mixing head, the damper on such side may be partially 95 or entirely closed and the damper on the other side partially or entirely opened, or the damper at each side may be opened more or less for exact regulation of the air supply. I thus avoid the objections of a varying 100 supply of air, due to the changeable outside wind pressure.

The flare plate 4 as shown may be made as an integral part of the pipe 3, partly severed, flattened out and bent up across the 105 inner end thereof, leaving a narrow emission slot 13 which is annularly arranged around the upper and side portions of pipe 3 and between the outer end of said pipe and the flare plate. The width of such slot 110

between the end of the pipe and the inner face of the plate may be accurately adjusted to any desired opening with regard to the volume to be produced and its degree 5 of expansion from the terminal of the burner.

As thus constructed, air in exactly regulated proportion will be drawn in by the 10 gas jet in the manner of an injector and the air and gas will become thoroughly mixed within the conduit 3, and especially as the mixture is projected against the flare plate 4. Thereupon, the mixture will escape through the slot 13 in the form of a partly 15 annular, very thin sheet or body of thoroughly mixed gas and air, which will be projected outwardly around the end of the burner in the form of a fan-tail jet. The combustion of the mixture will occur at 20 the outer fringe of the jet in the manner indicated at α in Fig. 6.

I claim:

1. A gas burner consisting of a hollow head having oppositely arranged air inlet 25 openings, each of said openings being provided with an individually adjustable damper and a burner pipe having a flare plate formed of a partly severed flattened portion of the pipe bent up across the open 35 end of the pipe with a narrow intervening annular slot.

2. A gas burner consisting of a hollow head having oppositely arranged air inlet openings, an air controlling damper pivotally secured on the face of each air opening 35 by a securing set screw, and a burner pipe having a flare plate formed of a partly severed flattened portion of the pipe bent up across the open end of the pipe with a 40 narrow intervening annular slot.

3. A gas burner consisting of a mixing chamber having an extended burner pipe provided with a terminal flare plate, and oppositely arranged air inlet openings each 45 having an individually adjustable control-

ling damper, and a gas inlet conduit extending through the mixing chamber into the burner pipe.

4. A gas burner consisting of a hollow head having laterally arranged air inlet 50 openings each provided with an individually adjustable damper, a burner pipe extending from the hollow head and provided with an integral flare plate extending across the open end thereof with an intervening 55 narrow annular slot, and a gas inlet conduit extending through the hollow head into the burner pipe.

5. A gas burner consisting of a hollow head having oppositely arranged air inlet 60 openings, an air controlling damper pivotally secured on the face of each air opening by a securing set screw, a burner pipe extending from the hollow head and provided with a flare plate, and a gas inlet conduit 65 extending through the hollow head into the burner pipe.

6. In a gas burner of the class described, a burner pipe having a flat terminal flare plate formed integral therewith and extending across the open end of the pipe with an intervening narrow annular slot, said plate projecting upwardly and to each side of said burner pipe.

7. In a gas burner of the class described, 75 a burner pipe having a terminal flare plate formed of a partly severed flattened portion of the pipe bent up across the open end of the pipe with an intervening annular slot.

8. In a gas burner of the class described, a burner pipe having a terminal flare plate formed of a partly severed flattened portion of the pipe bent up across the open end of the pipe with an intervening annular slot 85 of uniform width.

In testimony whereof I hereunto affix my signature.

JACOB E. COLEMAN.
